United States Patent Office

Des. 191,551
Patented Oct. 10, 1961

191,551

ICE MACHINE CABINET

Kenneth W. Duesenberg, St. Joseph, and Anthony M. Kulusic, Benton Harbor, Mich., assignors to Whirlpool Corporation, St. Joseph, Mich.

Filed Jan. 29, 1960, Ser. No. 59,202

Term of patent 14 years

(Cl. D67—3)

FIG 1.

FIG 2.

FIG. 3.FIG. 4FIGURE 1 is a perspective view of the Ice Machine Cabinet, showing our new design.

FIGURE 2 is a front elevational view thereof.

FIGURE 3 is a side elevational view taken from the left side of FIGURE 2.

FIGURE 4 is a sectional view taken on line 4-4 of FIGURE 2.

The back of the ice machine cabinet, not shown is substantially plain.

The dominant features of the design are shown in solid lines.

We claim:

The ornamental design for an ice machine cabinet, substantially as shown and described.
